UNITED STATES PATENT OFFICE.

HILLIARY B. McREE, OF PALMETTO, FLORIDA.

GAS AND OIL VENDING DEVICE.

1,375,526.

Specification of Letters Patent. Patented Apr. 19, 1921.

Application filed August 25, 1919. Serial No. 319,546.

To all whom it may concern:

Be it known that I, HILLIARY B. McREE, a citizen of the United States, residing at Palmetto, in the county of Manatee and 5 State of Florida, have invented new and useful Improvements in Gas and Oil Vending Devices, of which the following is a specification.

This invention relates to improvements in 10 liquid vending machines more particularly adapted for use in delivering gasolene and lubricating oils and the principal object of the invention is to provide means controlled by a coin for delivering a certain amount 15 of liquid after which the device is locked and no more liquid can be secured unless another coin is deposited.

The purpose of the invention is to provide 20 means whereby a customer may secure a supply of gasolene or oil at a service station by depositing the correct sum for the amount of gasolene desired so that the service of an attendant is not required. In this way the 25 station may be opened day and night for it is impossible to withdraw any of the liquid without depositing the correct sum.

Another object of the invention is to provide 30 a plurality of sets of devices whereby different quantities of liquid may be withdrawn from the tank by depositing coins of different denominations.

The invention also consists in certain other features of construction and in the combination and arrangement of the several 35 parts, to be hereinafter fully described, illustrated in the accompanying drawings and specifically pointed out in the appended claims.

In describing my invention in detail, reference 40 will be had to the accompanying drawings wherein like characters denote like or corresponding parts throughout the several views, and in which:—

Figure 1 is a sectional view of the invention.

Fig. 2 is a section on line 2—2 of Fig. 1.

Fig. 3 is a perspective view of the case.

Fig. 4 is an enlarged detail view of the lower end of the coin chute and its associated parts.

Fig. 5 is a sectional view of a modification.

Fig. 1 indicates a casing for containing the mechanism forming the subject matter 55 of the invention. This casing is to be located adjacent the usual pump 2 which is suit-

ably connected with the tank containing the gasolene or other fluid to be vended.

The piston 3 of the pump has its rod 4 provided with a rack 5 which is engaged by 60 a gear 6 located on the shaft 7, the journals of which are carried by one wall of the case 1 and by the bracket 8 secured to said case. The outer end of the said shaft is provided with a crank handle 9 by which 65 the shaft may be manually rotated to actuate the pump. The inner end of said shaft carries a beveled gear 10 which is loosely mounted thereon and is connected with the shaft by ratchet mechanism located in the 70 case 11. This gear 10 meshes with a like gear 12 carried by an upright shaft 13 located in the case. This upright shaft is provided with a toothed wheel 14 and with a worm 15. The toothed wheel 14 is adapted 75 to be engaged by a tooth 16 located on the locking bar 17, horizontally slidable on the guides 18 carried by the inner walls of the case. Springs 18' hold the bar with its teeth engaging the wheel. The worm 15 80 is engaged by a worm wheel 19 located on a horizontal shaft 20 mounted in the case and this shaft 20 is provided with a number of toothed wheels 21. A second horizontal shaft 22 is journaled in the case and this shaft 85 carries a number of toothed wheels 23 which are splined to the shaft so that they will rotate therewith but have sliding movement thereon. These wheels 23 are adapted to be moved longitudinally on the shaft by the 90 cams 24 and said shaft 22 is normally held in a certain position by the spring 25. Each cam is operated by a lever 26 which is pivoted at 27 and which is operated by a coin as hereinafter described. The lower end 95 of this lever is provided with an angle part 28 which is connected by a pin and slot connection with an arm 29 extending from one part of the cam. In this way when the lever is rocked the arm 29 will be forced 100 forwardly to bring the enlarged parts of the two parts of the cam together and thus slide the wheel 23 upon the shaft 22 and thus place said wheel into mesh with one of the wheels 21 on shaft 20. The parts are held 105 in this position by a latch bar 30 engaging a notch 31 in the angle part 28 of lever 26 so as to hold the lever in its projected position. After the wheel 23 makes one complete revolution a pin 32 thereon will strike 110 the latch bar and thus cause the same to release the lever 26 to permit said lever and

the cam part to return to normal position, when spring 33 will return wheel 23 to normal position and out of mesh with wheel 21. Spring 25 will then rotate shaft 22 back 5 to its normal position. I may locate a plurality of holes in each wheel 23 so the pin 32 may be adjusted.

The upper end of lever 26 is provided with a right-angle extension which extends 10 through a slot formed in the lower end of coin chute 34. A second lever 35 co-operates with the upper end of lever 26 to engage the coin and this lever 35 is engaged by the spring 36 which tends to hold both lever 15 35 and lever 26 in position to form a rest for the coin and with the cam part in inoperative position. These levers also have a pin and slot connection with a slide bar 37, the front end of which passes through an 20 opening in the locking bar 17 where it is provided with a head 37' so that in its forward movement the sliding bar will pass through the opening without moving the locking bar, but in its rearward movement 25 engages the bar and causes it to move rearwardly with it and thus moves the tooth 16 out of engagement with the wheel 14.

The coin is forced between the levers 26 and 35 to rock said levers by the arms 38 30 which have their upper ends provided with inwardly projecting portions engaging with the slots 39 formed in the chute. The lower ends of these arms are connected to a crank arm 40 by a link 41 and said arms 38 pass 35 through guides 42. Said arms are of curved formation so that when they are brought downwardly by rotation of shaft 43 which carries arm 40 the guides will cause them to approach each other and thus throw their 40 upper ends into the chute and against the coin resting upon the upper ends of levers 26 and 35. As the coin is forced between said levers by said arms it will force the levers apart, thus causing lever 26 to actuate 45 the cam part to move the wheel 23 into engagement with the wheel 21 and lever 35 will cause the rod 37 to move the locking bar to withdraw the tooth 16 from the wheel 14. This will permit the shaft 7 to be rotated 50 by its crank handle to cause the pump to pump up the liquid. The shaft 7 may be rotated until it causes the wheel 23 to make a complete revolution when the pin 32 on said wheel 23 will strike the latch bar 55 and release the lever 26 so that the parts are returned to normal position and the shaft 7 locked against further movement by the tooth 16 on the locking bar 17 engaging the wheel 14 or shaft 13.

60 After the coin passes the levers 26 and 35 it will drop into a suitable receptacle or it may fall directly on to the floor of the case. The shaft 43 has one end extending through the case where it is provided with a crank handle 43'.

The drawings show three sets of coin controlled devices so that three coins of different denominations may be deposited to secure different quantities of liquid. The parts may be so proportioned that a quantity of liquid may be drawn commensurate to the coin deposited. 70

In the modification shown in Fig. 5 the means for forcing the coin between the levers consists of an arm 45 on the shaft 43*, 75 said arm operating through slot 39' in the coin chute 34'.

It will of course be understood that any desired number of coin chutes and their associated parts may be used according to 80 the size of the station and the device may be made to deliver any desired amount of liquid in one operation of the pump.

It is thought from the foregoing description that the advantages and novel features 85 of my invention will be readily apparent.

I desire it to be understood that I may make changes in the construction and in the combination and arrangement of the several parts, provided that such changes 90 fall within the scope of the appended claims.

What I claim is:—

1. A device of the class described comprising liquid delivery means, manually operated means for actuating the same, a shaft 95 rotatably connected with the manually operated means, locking means for said shaft, a pair of transversely arranged shafts, means for rotating one of said shafts by the first mentioned shaft, a gear on each of 100 the transversely arranged shafts, one of said gears having sliding movement on its shaft and being normally out of mesh with the other gear, a cam member for moving said sliding gear into mesh with the other gear, 105 coin controlled means for releasing the locking means and for actuating the cam member, such means including a pivoted lever actuated by the coin and connected with the cam member, a latch bar engaging said lever 110 for holding the locking means in inoperative position and the gears in mesh and a projection on the sliding gear for moving the latch bar into releasing position when said gear makes a complete revolution. 115

2. A device of the class described comprising liquid delivery means, manually operated means for actuating the same, a shaft 120 rotatably connected with the manually operated means, locking means for said shaft, a pair of transversely arranged shafts, means for rotatably connecting one shaft of 125 said shafts with the first mentioned shaft, a plurality of gears on said transversely arranged shafts, the gears on one shaft having sliding movement thereon, spring means for normally holding said sliding gears out of mesh with the gears on the other transverse shaft, cam members for moving said sliding gears into mesh with said other 130

gears, a pivoted lever connected with each cam member and adapted to be operated by a coin, means for connecting said lever with the locking means to move said means into 5 unlocking position when the lever is actuated by a coin, a latch bar engaging said lever for holding it in position with the locking means in inoperative position and the gears in mesh and a projection on each 10 sliding gear for engaging said latch bar for releasing the same when the gear makes a complete revolution.

3. A device of the class described comprising liquid delivery means, manually operated means for actuating the same, a shaft rotatably connected with said manually operated means, a second shaft rotatably connected with the first shaft, a gear on said 15 second shaft, a third shaft, a gear slidably mounted on the third shaft and normally 20 out of mesh with the gear on the second shaft, a cam member for moving the sliding gear into mesh with the other gear, a pivoted lever connected with said cam member and adapted to be rocked by a coin, locking 25 means for the first mentioned shaft, a rod connecting the same with the coin operated lever, a latch bar for holding the pivoted lever in position with the locking means in inoperative position and the gears in mesh, 30 adjustable means on the sliding gear for releasing said latching bar when said gear makes a complete revolution and means for forcing the coin past the lever.

In testimony whereof I affix my signature. 35
HILLIARY B. McREE.
